DESIGN FOR A DIAPER SCRUBBER

Ralph Houston Kingdon, Delavan, Wis.

Application August 30, 1943, Serial No. 111,021

Term of patent 3½ years

To all whom it may concern:

Be it known that I, Ralph Houston Kingdon, a citizen of the United States, residing at Delavan, in the county of Walworth and State of Wisconsin, have invented a new, original, and ornamental Design for a Diaper Scrubber, of which the following is a specification, reference being had to the accompanying drawing, forming part thereof.

Fig. 2 is an edge view thereof.

I claim:

The ornamental design for a diaper scrubber, substantially as shown.

RALPH HOUSTON KINGDON.
